United States Patent Office

Des. 180,237
Patented May 7, 1957

180,237

DICTATING MACHINE

Maurice E. Libson, North Haven, Conn.
Application April 6, 1956, Serial No. 40,952

Term of patent 14 years

(Cl. D26—14)

Fig. 1

Fig. 2

Fig. 3

Fig. 4

Fig. 1 is a top plan view of a dictating machine, showing my new design.

Fig. 2 is an elevation of the same as viewed from one side.

Fig. 3 is an elevation of the same as viewed from the opposite side.

Fig. 4 is a front elevational view of the same.

The dominant features of the design reside in the portions shown in full lines. The dotted lines on the drawing indicate the supporting strap.

I claim:

The ornamental design for a dictating machine, substantially as shown and described.
